(57) **CLAIM**

The ornamental design for a trash receptacle and advertising kiosk, as shown and described.

DESCRIPTION

FIG. 1 is a front perspective view of the trash receptacle and advertising kiosk showing our new design;

FIG. 2 is a top plan view thereof;

FIG. 3 is a front elevational view thereof;

FIG. 4 is a left side elevational view, the right side being a mirror image thereof;

FIG. 5 is a rear elevational view thereof; and,

FIG. 6 is bottom plan view thereof.

The broken line showing in the figures is for illustrative purposes only and forms no part of the claimed design.
